UNITED STATES PATENT OFFICE.

JOHN I. BELLAMY, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed July 22, 1921, Serial No. 486,783. Renewed May 19, 1928.

The present invention relates to automatic telephone systems in general, but is concerned more particularly with large multi-office automatic systems; and the object, briefly stated, is the provision of a new and improved trunking arrangement in a multi-office automatic system, whereby such switches as are not actually needed in any particular office may be omitted without altering 10 the number of digits in the telephone numbers of the lines that terminate in that office.

The object above pointed out is not broadly new, being disclosed in the prior U. S. patent issued to Martin on August 30, 1927, No. 1,640,551. The present invention, however, 15 provides a number of new and desirable features as will be pointed out fully hereinafter.

A special feature of the invention relates to improved operation in a so called drop 20 back selector.

Another feature relates to an improved test circuit, whereby a number of lines can be tested or rotated over selectively with much greater speed without sacrificing accuracy, 25 while another feature relates to improved means for controlling the test circuit so as to prevent any operation of the relays or various parts of the mechanism of a selector switch, when it is releasing, due to the test 30 wiper passing over grounded test contacts.

Another feature which may be pointed out briefly at this time relates to an improved circuit arrangement whereby the release trunk conductor of a selector switch is automatically 35 grounded during the releasing operation so that in case the selector becomes mechanically stuck in an off normal position it is automatically cut out of service.

A still further feature of the invention relates to improved means for controlling the 40 slow acting release relay so as to render it more positive in action and capable of carrying a larger spring combination than heretofore.

As to certain of the features, this application 45 may be considered as being an improvement on the application of C. E. Lomax, S. N. 407,996, filed September 3, 1920.

Referring now to the drawings, Fig. 1 50 shows a selector which mechanically is of the well known vertical and rotary type and accordingly has its bank contacts arranged in horizontal rows or levels. The circuits of

this selector include various features of the invention and will be explained fully here- 55 inafter.

Fig. 2, shows a selector similar to the one shown in Fig. 1 with the proposed digit absorbing or drop back feature added and with a different arrangement for controlling the 60 test circuit so as to render it inoperative during the releasing operation.

Fig. 3, is a schematic layout showing a 65 trunking arrangement in which the proposed drop back selector may be used very profit- ably.

Referring now particularly to Fig. 3, which shows a portion of the trunking system in an automatic telephone system having a capacity of 100,000 lines, the lines are assumed to terminate in ten different offices which are so interconnected with trunk lines as to form an integral system. The office 70 which is reached when the digit 2 is dialled as well as the other offices in the system, with the exception of the one which is reached when the digit 3 is dialled, may be equipped to their full capacity, while for the purpose of illustration it will be assumed that the office to which connection is extended when the digit 3 is dialled has for the time being 75 no more than 1000 telephone lines terminating in it.

In order to point out the trunking arrangement more clearly, it will be assumed that 80 the subscriber at substation A desires to call the subscriber at substation A². With the assumption as noted, the connection may be extended as follows: From the substation A, by way of the individual line switch C, first or office selector D, second or thousands selector E, third or hundreds selector F', and the connector H', to the substation A². This, it will be noted, is the usual trunking arrangement. Assuming now that the subscriber at substation A calls the subscriber at substation A', the connection may be traced as follows: From the substation A, by way of the individual line switch C, first or office selector D, third or hundreds selector F, and the connector H, to the substation A'. This latter connection extends over a path similar to the one of the substation A² with the exception that it does not 85 pass through any second or thousands selector. It is obvious, in view of the fact that 90 95 100 105

there is only one "thousands" group of lines terminating in that office, that no thousands selector is needed. Now it is necessary only to introduce in the system an extra digit so as to make the telephone numbers in this office have the same number of digits as the ones in the other offices. As has been before intimated, this is accomplished in the system disclosed herein by arranging the selector F to drop back or restore to normal when the first digit is dialled, after connection is obtained with it, and to operate like a regular selector when the following digit is dialled.

It is desirable to be able not only to assign numbers having the desired number of digits but also to be able to assign numbers that may be retained even after the office has reached its ultimate growth.

As is well known, a full 10,000 line office may consist of a main office in which part of the lines terminate and one or more sub-offices of probably 1000 lines each. Assuming that when the office under discussion is first installed, most of the lines, owing to their relatively short length, logically terminate in the main office but other lines owing to their great length will, together with still others to be cut in later, be terminated eventually in a sub-office of 1000 lines capacity, the lines that eventually will be terminated in the sub-office must necessarily be reached, after the sub-office is installed, by dialling a different second or "thousands" digit than is dialled to reach any "thousands" group of lines in the main office with which the sub-office is associated. This situation does not cause any difficulty to be encountered in the present system, however, for the reason, that with the drop back selectors arranged to absorb the "thousands" digit regardless of what that digit is the numbers may be assigned not only in any particular "thousands" group of lines but in each and every "thousands" group of lines.

The apparatus, having thus been described in a more or less general manner, will now be described in connection with a detailed description of its operation. For this purpose it will be assumed that the subscriber at substation A desires to obtain connection with the subscriber at substation A'. When the receiver is removed at substation A the individual line switch C is operated to extend the connection to an idle first selector, and assuming that the first selector D is the one to which the connection is extended the line and release relays 17 and 18, Fig. 1, are energized in the usual manner. Release relay 18, upon energizing, opens a point in the circuit of the release magnet at armature 30 at the same time preparing the circuit of the vertical magnet 23; disconnects the off normal contacts 26 from the release trunk conductor 15 at armature 28 and closes a point in the circuit of switching relay 21; and at

armature 29 places ground on release trunk conductor 51 thus establishing the usual holding circuit for line switch C.

The calling subscriber now operates his calling device in accordance with the first digit of the desired number, whereupon the circuit of line relay 17 is interrupted a corresponding number of times. Each time line relay 17 deenergizes in response to one of these interruptions it closes at armature 25 the following circuit: From ground, by way of the resting contact of armature 37 and said armature, armature 25 and its resting contact, relay 19, armature 30 and its working contact, and vertical magnet 23 to battery. By the operation of the vertical magnet, the shaft and wipers are raised step by step until the latter stand opposite the desired level of contacts, which in this case is the level in which the selector F terminates. Relay 19 is energized in series with the vertical magnet and being slow acting retains its armatures attracted throughout the vertical movement. At armature 31 relay 19, upon energizing, places a shunt around the major part of the winding of release relay 18. This has two distinct effects. One effect is that there is an increased flow of current through the part of the winding which is not short circuited, and which is composed of larger wire than the remainder of the winding, each time the circuit of the release relay 18 is closed, thereby giving more lines of force, or in effect increasing the slowness of the relay. Another effect is that the part of the winding which is short circuited has the same effect on the relay as placing an additional copper slug thereon, thereby further increasing the slowness of the relay. As a further result of the operation of slow acting relay 19 it disconnects the rotary magnet 24 from the upper winding of stepping relay 20 and connects it to the lower winding of the said relay at armature 32. Stepping relay 20 energizes but rotary magnet 24 does not energize at this time because of the high resistance of the lower winding of stepping relay 20. Upon energizing, stepping relay 20 prepares a circuit for the rotary magnet 24 at armature 33.

At the end of the vertical movement slow acting relay 19 deenergizes, removes the short circuit from around the lower part of the winding of release relay 18 at armature 31, and at armature 32 shifts the circuit of rotary magnet 24 from the lower winding of stepping relay 20 to the upper winding of the said stepping relay. Rotary magnet 24 now energizes and stepping relay 20 is maintained energized over the following circuit: From ground by way of off normal contacts 26, armature 28 and its working contact, working contact of armature 33 and said armature, resting contact of the armature of rotary magnet 24 and said armature, upper

- winding of stepping relay 20, normally closed contacts controlled by armature 32, and rotary magnet 24 to battery. Upon energizing, rotary magnet 24 steps the shaft and wipers 5 45-47, inclusive, into engagement with the first set of contacts in the level opposite which they are raised, at the same time opening its own circuit and that of stepping relay 20, whereupon they both deenergize.
- 10 Stepping relay 20, upon deenergizing, opens another point in the initial circuit of its own upper winding and consequently in the circuit of the rotary magnet 24 at armature 33, and rotary magnet 24, upon deenergizing, 15 closes again a point in its own circuit and that of the upper winding of stepping relay 20. From this point the operation depends upon whether the trunk line terminating in the first set of contacts is busy or idle. If it 20 is busy, there is a ground potential on the test contact thereof and the stepping relay and the rotary magnet energize again over the following circuit: From ground by way of the busy test contact, test wiper 46, armature 36 and 25 its resting contact, and thence by way of a previously traced circuit through the upper winding of stepping relay 20 and rotary magnet 24 to battery. Stepping relay 20, upon energizing, closes the previously traced 30 local circuit for itself and for the rotary magnet at armature 33, and rotary magnet 24, upon energizing, advances the wipers into engagement with the next set of contacts and again opens its own circuit and that of the 35 stepping relay, whereupon the stepping relay and rotary magnet deenergize again. This cycle of operation is repeated over and over until an idle or ungrounded test contact is reached.
- 40 When an idle set of contacts is reached, or one in which the test contact is not grounded, switching relay 21, being no longer short circuited, energizes over the following circuit: From ground by way of off normal contacts 45 26, armature 28 and its working contact, switching relay 21 and thence by way of a previously traced circuit to battery by way of the upper winding of stepping relay 20 and rotary magnet 24. Neither stepping relay 20 nor rotary magnet 24 are energized over this 50 circuit because of the high resistance of switching relay 21 but the latter relay is energized and at armature 37 removes ground from the armature of the line relay; grounds 55 the test wiper 46, so as to make the seized trunk busy immediately, at armature 36; connects up the release trunk conductor 15 with the test wiper 46 at armature 35; and at armature 34 and 33 disconnects the line conductors 60 14 and 16 from the upper and lower windings of line relay 17 and extends them by way of armatures 34 and 38 and their working contacts, line wipers 45 and 47, and from thence (assuming that the trunk line terminating in 65 the bank contacts 48-50 inclusive, is the one selected) by way of bank contacts 48 and 50, trunk conductors 51 and 53, and armatures 84 and 88 and their resting contacts, to the upper and lower windings of line relay 60 of the drop back selector F. Line relay 60, upon 70 energizing, closes the circuit of release relay 61 at armature 69. Release relay 61, upon energizing, opens a point in the circuit of release magnet 66 at armature 75, at the same time preparing a circuit for the vertical magnet 67; disconnects the off normal contacts 75 from the release trunk conductor 52 and closes a point in the circuit of switching relay 65 at armature 73; connects up the test wiper 90 at armature 72; and at armature 74 places ground on release trunk conductor 52, thereby closing a holding circuit for the selector D and line switch C before the slow acting release relay 18 of the selector D has had time 80 to deenergize.
- 85 The calling subscriber now operates his calling device in accordance with the second digit of the desired number or the digit which ordinarily picks out the thousands group of lines in a 100,000 line system. In the present case the digit for which the calling device is turned is immaterial as far as the final result is concerned and will be determined by what thousands group the called line will be terminated in after the number of lines has increased to more than one thousand. Each time line relay 60 deenergizes in response to the operation of the calling device at the calling substation, it closes at armature 69 the following circuit: From ground by way of the resting contact of armature 87 and said armature, armature 69 and its resting contact, armature 75 and its working contact, relay 63, and vertical magnet 67 to battery. By the operation of the vertical magnet, the shaft and wipers 89-92, inclusive, of the selector F are raised step by step until the latter stand opposite the desired level of contacts. Relay 63 is energized in series with the vertical magnet and being slow acting retains its armature 90 attracted throughout the vertical movement and at armature 81 places a shunt around the lower part of the winding of release relay 61 while at armature 82 it shifts the circuit of the rotary magnet from the upper winding of stepping relay 64 to the lower winding of the said relay. Upon energizing, stepping relay 64 prepares a circuit for the rotary magnet at armature 83.
- 100 At the end of the vertical movement, slow acting relay 63 deenergizes; removes the shunt from around the lower part of the winding of release relay 61 at armature 81, and at armature 82 disconnects the rotary magnet 63 from the lower winding of stepping relay 64, whereupon stepping relay 64 deenergizes. With relay 63 deenergized, the following circuit may be traced: From ground by way of the upper winding of relay 62, resistance R, normally closed contacts 105
- 110 115 120 125 130

controlled by armature 77, working contact of off normal spring 80 and said spring, normally closed contacts controlled by armature 82, and rotary magnet 68 to battery. Rotary magnet 68 is not energized over the above traced circuit on account of the high resistance of the upper winding of relay 62 and the resistance R. Relay 62, being marginally adjusted, operates its armatures only part way at this time and accordingly disconnects armature 76 from its resting contact but does not connect it with its working contact; places armatures 77 and 78 into contact with their respective working contacts but does not open the normally closed contacts controlled by the said armatures; operates armature 79 sufficiently to bring it into engagement with its working contact. With relay 62 thus partly operated, the following circuit is closed for release magnet 66: From ground by way of release trunk conductor 52, normally closed contacts controlled by armature 78, working contact of armature 78 and said armature, off normal contacts 71, and release magnet 66 to battery. By the operation of the release magnet, the shaft and wipers of the selector F are restored to normal position, the initial circuit of the release magnet being opened at the off normal contacts 71 by the shaft when it reaches normal position. Upon the off normal contacts 71 being separated, a shunt is removed from around the lower winding of relay 62 whereupon the said relay energizes over the following circuit: From ground by way of release trunk conductor 52, lower winding of relay 62, working contact of armature 79 and said armature, and release magnet 66 to battery. Release magnet 66 deenergizes in series with the lower winding of relay 62 owing to the high resistance of the said lower winding but the relay 62 now pulls all the way up, thereby opening the normally closed contacts controlled by armatures 77 and 78 and placing armature 76 into engagement with its working contact. It will be seen now that the net result of the dialling of the second digit in the number, or the first digit after the selector F has been reached, is that the said selector has operated in its vertical movement; restored itself to normal position, and relay 62 has become locked up.

The calling subscriber now operates his calling device in accordance with the next digit of the desired number, whereupon the vertical magnet 67 is energized a corresponding number of times to step the switch shaft and wipers up to the desired level and slow acting relay 63 and stepping relay 64 are energized in a manner previously described. At the end of the vertical movement, slow acting relay 63 deenergizes and transfers the circuit of the rotary magnet from the lower to the upper winding of stepping relay 64. Stepping relay 64 is maintained energized momentarily and rotary magnet 68 energizes over the following circuit: From ground by way of off normal contacts 70, armature 73 and its working contact, working contact of armature 83 and said armature, resting contact of the armature of rotary magnet 68, and said armature, upper winding of stepping relay 64, armature 76 and its working contact, normally closed contacts controlled by armature 82, and rotary magnet 68 to battery. Upon energizing, rotary magnet 68 opens its own circuit and also that of the upper winding of stepping relay 64. Stepping relay 64, upon deenergizing, opens another point in its own circuit and in that of rotary magnet 68, and rotary magnet 68, upon deenergizing, closes the first mentioned point in its own circuit and that of the stepping relay 64.

The operation now depends upon whether the trunk line terminating in the first set of contacts is busy or idle. If it is busy there is a ground potential on the test contact thereof and stepping relay 64 and rotary magnet 68 energize again over the following circuit: From ground by way of the grounded test contact, test wiper 90, armature 86 and its resting contact, armature 72 and its working contact, resting contact of the armature of rotary magnet 68 and said armature, and thence by way of a previously traced circuit through stepping relay 64 and rotary magnet 68 to battery. Upon energizing, stepping relay 64 closes again in the previously described local circuit for itself and the rotary magnet, and the rotary magnet, upon energizing, advances the shaft and wipers 88-91, inclusive, into engagement with the next set of contacts, at the same time opening its own circuit and that of stepping relay 64, whereupon they both deenergize. This same cycle of operations is repeated over and over until an idle or ungrounded test contact is reached.

When an idle set of contacts is reached switching relay 65 energizes over the following circuit: From ground by way of off normal contacts 70, armature 73 and its working contact, switching relay 65, and thence to battery by way of previously traced circuit, through the upper winding of stepping relay 64 and rotary magnet 68. Neither stepping relay 64 or rotary magnet 68 energizes over this circuit because of the high resistance of switching relay 65. Upon energizing, switching relay 65—assuming that the trunk line terminating in bank contacts 92-94, inclusive, is the first one found to be idle—switches the connection through by way of armatures 84 and 88 and their working contacts, wipers 88 and 91, bank contacts 92 and 94, line conductors 95 and 97, to the upper and lower windings of the line relay of connector H, Fig. 3. The line and release relays of connector H (not shown) now energize in the usual manner and the latter places ground on

release trunk conductor 96 so as to establish the usual holding circuit before the slow acting release relay 61 of the selector F has had time to deenergize.

5 The calling subscriber now manipulates his calling device in accordance with the remaining two digits of the desired number, whereupon the connector H is operated in the usual manner to connect with the line of 10 substation 'A', and when the connection is finally completed and the calling subscriber has answered, the calling and called subscribers may converse with each other as desired, the talking circuits that are shown 15 being outlined by the heavy conductors.

When the conversation is completed the two subscribers replace their receivers. When the receiver is replaced at substation A the circuit of the line relay of connector 20 H is opened, whereupon the line and release relays of the said connector deenergize and the connector H is at once restored to normal position in the usual manner. As soon as 25 ground is removed from release trunk conductor 96 by the deenergization of the release relay of connector H, the circuit for switching relay 65 and relay 62 of selector F and switching relay 21 of selector D, as well as the circuit for the switching relay of the line 30 switch C is opened, and the said relays immediately deenergize. In the selector F, relay 62, upon deenergizing, does not perform any particular function at this time but switching relay 65 upon deenergizing places 35 ground on release trunk conductor 52 again by way of off normal contacts 70, and armature 73 and its resting contact, and the resting contact of armature 85 and said armature. This is done primarily to prevent the selector 40 F from being taken for use again in case it becomes mechanically stuck in an off normal position. In the normal course of events, however, the said selector does not become stuck and release magnet 66, upon energizing, in series with the resting contact of armature 45 87 and said armature, armature 69 and its resting contact, armature 75 and its resting contact, and off normal contacts 71, restores the switch shaft and wipers to normal 50 position, ground being removed from release trunk conductor 52 at off normal contacts 70 and the circuit of the release magnet 66 being opened at off normal contacts 77 by the shaft when it reaches normal position.

55 It will be noted in connection with the test circuit of the selector F that the said circuit is closed at armature 72 and its working contact only while release relay 61 is energized and consequently is always open during the 60 releasing operation, and accordingly there is no possible chance for either stepping relay 64 or rotary magnet 68 to become energized while test wiper 90 is passing over grounded test contacts during the releasing operation.

65 In the selector D, switching relay 21, upon

deenergizing in response to the removal of the ground potential from release trunk conductor 52, closes at armature 36 a circuit for rotary magnet 24 as follows: From ground, which has been replaced on release trunk conductor 52 upon the falling back of switching relay 65 of selector F, by way of test contact 49, test wiper 46 and thence by way of a previously traced circuit to rotary magnet 24. At the same time switching relay 21 70 closes at armature 37 the following circuit, for release magnet 22: From ground by way of the working contact of armature 37 and said armature, armature 25 and its resting contact, relay 19, armature 30 and its resting contact, off normal contacts 27, and release magnet 22 to battery. Rotary magnet 24, stepping relay 20, release magnet 22, and relay 19 now energize simultaneously. Rotary magnet 24, upon energizing, steps the 80 wipers forward one step in the usual manner and at the same time opens its own circuit including the upper winding of stepping relay 20 and falls back again; and relay 19 upon energizing shifts the circuit of the rotary magnet from the upper to the lower winding of stepping relay 22, thereby maintaining the stepping relay 20 energized. By the operation of the release magnet 22, the shaft and wipers of the selector D are 85 restored to normal position in the usual manner, the circuit of the release magnet being opened at off normal contacts 27 by the switch shaft when it reaches normal position. Relay 19, upon deenergizing after the 90 off normal contacts 27 have opened, shifts the circuit of the rotary magnet 24 from the lower to the upper winding of stepping relay 20, whereupon the said stepping relay deenergizes. It will be noted that a ground potential is replaced upon release trunk conductor 15, by way of off normal contacts 26, armature 28 and its resting contact, and the resting contact of armature 35 and said armature, as soon as switching relay 21 deenergizes. This is done for the same reason as explained in connection with the selector F. Obviously the ground potential is removed from release trunk conductor 15 at off normal contacts 26 as soon as the shaft of selector D 105 reaches normal position.

110 It may be pointed out here that in case it is so desired the drop back selector F may be arranged to drop back only upon the calling of a particular digit, by merely changing the spring 80 from an off normal spring to a spring that operates only when the shaft is stepped up to a particular level. The circuits do not need to be altered when the change is made but work equally well either 115 way.

The various features of the invention, having been thus described, will now be pointed out more fully in the appended claims.

What I claim as my invention is:

1. In a telephone system, a subscriber's line, means including a first selector, a second selector, and a connector for connecting the said first line with a second line, 5 means including said first selector, another second selector, a third selector, and another connector for connecting said first line with a third line, telephone numbers for said second and third lines having the same number 10 of digits, and means for automatically releasing the first mentioned second selector whenever the said second line is called in order to cancel one of the digits in the number.

2. In a multi-office telephone system, two 15 subscribers' lines terminating in two different offices, telephone numbers for said lines having the same number of digits, a calling subscriber's line terminating in a third office, means including a first selector in the third office and a certain number of serially related switches in the first office for connecting said calling line with the said first line, means including said first selector and a series of switches in the second office for connecting said calling line with the said second line, said second series of switches being greater 25 by one than the said first series, and means for automatically releasing one of the said switches in the first office whenever said first 30 line is called in order to cancel one of the digits in the number.

3. In a multi-office telephone system, a plurality of offices each having the same ultimate capacity, blocks of telephone numbers assigned to said offices, the numbers in each 35 block having the same number of digits as the numbers in the other blocks, serially related groups of switches in each office, there being a lesser number of groups in some 40 offices than in the others, and means including drop-back second selectors in those offices which have less groups of switches than the others for making the numbering system conform to the number of groups in use.

4. In a multi-office telephone system, a plurality of offices each having the same ultimate capacity, blocks of telephone numbers assigned to said offices, the numbers in each 50 block having the same number of digits as the numbers in the other blocks, serially related groups of switches in each office, there being a lesser number of groups in some offices than in the others, and means including drop-back selectors in those offices which 55 have less groups of switches than the others for cancelling the proper number of digits in the telephone numbers of lines terminating in such offices in order to make the numbering of such lines conform to the number of 60 groups in use.

5. In a multi-office telephone system, a plurality of offices each having the same ultimate capacity, blocks of telephone numbers assigned to said offices, the numbers in each 65 block having the same number of digits as

the numbers in the other blocks, serially related groups of switches in each office, there being a lesser number of groups in some offices than in the others, and means only in those offices which have less groups of switches 70 than the others for making the numbering system conform to the number of groups in use, said means comprising circuit arrangements in a particular group of switches for causing such switches to automatically release the first time they are operated.

6. In a digit absorbing or drop back selector having primary and secondary movements, a release magnet, a relay, a circuit for partially energizing said relay at the completion of the primary movement, a circuit for said magnet closed by said relay, a circuit for completely energizing said relay as soon as the switch is restored, and contacts controlled by said relay for altering the switch circuit so that a subsequent primary movement will be followed automatically by the secondary movement.

7. In a telephone system, an automatic switch for use in connecting calling and called lines, a quick acting line relay and a slow acting release relay for said switch, a circuit for said release relay closed by said line relay through normally open contacts thereon, means for momentarily deenergizing said line relay to operate said switch, and means for increasing the current in the said circuit of said release relay while said switch is operating.

8. In a telephone system, an automatic switch for use in connecting calling and called lines, said switch having primary and secondary movements, a quick acting line relay and a slow acting release relay for said switch, a circuit for said slow acting relay 100 closed by said quick acting relay, a second slow acting relay energized during the primary movement of said switch and deenergized at the end thereof, and contact springs actuated by said second slow acting relay 105 for short circuiting a portion of the winding of said first slow acting relay.

9. In a telephone system, a selector switch for use in connecting calling and called lines, said switch having directive primary and automatic secondary movements, a stepping relay controlling the secondary movement, a pair of off normal contacts, a circuit for said relay including said pair of off normal contacts, means for releasing said switch, and a test circuit also including said pair of off normal contacts for rendering said switch busy while releasing.

10. In a telephone system, a selector switch for use in connecting calling and called lines, said switch having directive primary movement and automatic secondary movement, a secondary motor magnet and a stepping relay, a test wiper, a circuit for energizing said magnet and said relay including the said test 125 130

- wiper, said magnet and relay being connected in the circuit in series, and contacts on said stepping relay for closing said circuit over a path excluding said test wiper.
- 5 11. In a telephone system, an automatic switch having wipers, said wipers having a normal position, means for moving said wipers from their normal position to effect a connection, means for subsequently releasing said wipers to said normal position, a relay controlling the electrical connection of said wipers to said switch, a pair of off normal contacts, a test conductor for said switch, and a circuit extending through said off normal contacts and contacts on said relay for applying a guarding potential to said test conductor during the restoration of said wipers to their normal position.
- 10 12. In an automatic switching device, a line relay, a release relay, contacts on said line relay through which current is supplied to said release relay, and means for increasing the amount of current supplied to said relay through said contacts while said line relay is being operated to control the device.
- 15 13. In a telephone system, a selector switch for use in connecting calling and called lines, said switch having directive primary movement and automatic secondary movement, a secondary motor magnet, a stepping relay and a switching relay, a test wiper, a circuit for energizing said magnet and stepping relay including said test wiper, said magnet and stepping relay being connected in the circuit in series, contacts on said stepping relay for closing said circuit over a path excluding said test wiper, and means for energizing said switching relay in a circuit including said magnet, stepping relay and switching relay in series.
- 20 14. In a telephone system, a selector switch for use in connecting calling and called lines, said switch having directive primary movement and automatic secondary movement, a secondary motor magnet, a stepping relay and a switching relay, means for energizing said magnet and stepping relay in series to control the automatic secondary movement, and means for energizing said switching relay in a circuit in series with said magnet and stepping relay when the automatic secondary movement is completed.
- 25 15. In a digit absorbing device having an initial and a subsequent directive movement wherein said device automatically releases after the initial movement, a two-step relay, a circuit for operating said relay in its first step responsive to the initial movement to cause the release of said device, a circuit for operating said relay in its second step responsive to the device being restored, and means controlled by said relay to prevent a second automatic releasing operation after the subsequent directive movement.
- 30 In witness whereof, I hereunto subscribe my name this 15th day of July, A. D., 1921.

JOHN I. BELLAMY.
